UNITED STATES PATENT OFFICE.

WILLIAM H. PAYNE, OF SOUTH HAVEN, MICHIGAN.

DESIGN FOR A DUST-PAN.

SPECIFICATION forming part of Design No. 28,025, dated December 14, 1897.

Application filed October 25, 1897. Serial No. 656,374. Term of patent 14 years.

To all whom it may concern:

Be it known that I, WILLIAM H. PAYNE, a citizen of the United States, residing at the city of South Haven, in the county of Van Buren and State of Michigan, have invented a certain new and useful Design for Dust-Pans, of which the following is a specification.

My invention relates to a design for a dust-pan, and especially to that style of dust-pan which is held in position by the foot of the user.

My invention relates particularly to the dust-pan illustrated in the accompanying drawings, in which—

Figure 1 is a perspective front view of the dust-pan, and Fig. 2 is a longitudinal sectional elevation.

The leading features of my design are the body portion, the front A of which is formed somewhat like the front of a dust-pan and extends upwardly and rearwardly and is formed

into a conical-shaped hood A' over the rear. The handle B is attached to the projecting point and curved under and is secured to the front portion A, as clearly appears in Fig. 2. The front bears the usual strengthening-corrugations.

The design is such that the dust-pan can be constructed from a single sheet of metal, though that of course is not an essential of the design.

Having thus described my invention, what I claim is—

A design for a dust-pan substantially as described and shown.

In witness whereof I have hereunto set my hand and seal in the presence of two witnesses.

WILLIAM H. PAYNE. [L. S.]

Witnesses:

JOHN W. ADAMS,

VENE E. CHAPPELL.
